UNITED STATES PATENT OFFICE.

FRANK MARZAK, OF BROOKLYN, NEW YORK, ASSIGNOR OF ONE-HALF TO ANTON SAMOKISZCZUK, OF BROOKLYN, NEW YORK.

FOLDING CHAIR.

1,374,213.

Specification of Letters Patent.

Patented Apr. 12, 1921.

Application filed April 26, 1920. Serial No. 376,497.

To all whom it may concern:

Be it known that I, FRANK MARZAK, citizen of the United States, and resident of Brooklyn, in the county of Kings and State 5 of New York, have invented certain new and useful Improvements in Folding Chairs, of which the following is a specification.

This invention relates to combination tables and chairs, or the like, and has for its 10 main object the provision of a table having pivotally attached thereto collapsible chairs which may at will be extended and withdrawn from their normal place of concealment under the top panel of the table, or, 15 after use, they may be collapsed and concealed under said panel. My device is of particularly great value to children in that the same may provide a playing table and chairs integral therewith of small size and compact construction, which will occupy little space and will not obstruct floor space 20 or passages.

The above and other objects will become apparent in the description below, in which 25 characters of reference refer to like named parts in the drawings.

Referring briefly to the drawings, Figure 1 is a plan view of my device, showing one chair extended.

30 Fig. 2 is a front elevational view of the same.

Fig. 3 is a front elevational view showing my invention applied to a sewing machine, with the chair concealed.

35 Fig. 4 is a side elevational view of the same with the chair extended.

Fig. 5 is a cross-sectional view taken on the plane 5—5 of Fig. 6.

Fig. 6 is a side elevational view of the 40 device shown in Figs. 1 and 2.

Fig. 7 is a view of a modification of Fig. 4.

Fig. 8 is an enlarged view showing how the chair is attached to the floor when used with a fixed sewing machine.

45 Fig. 9 illustrates another modification of Fig. 4.

Fig. 10 is an enlargement of a part of Fig. 9.

Referring now in detail to the drawings, 50 the numeral 1 represents the panel of a table of substantially common construction, supported upon legs 2. Cross-bars 7 are mounted diagonally under said panel and supported in said legs; and immediately under said cross-bars a second panel 18 is

mounted. Thus, four compartments 18^a are provided, in which may be placed articles as desired in the use of the device, such as playing cards, small toys, blocks, etc.

At the foot of each leg 2 a metal brace 60 8 is mounted, and a pivot 9 is therein provided for the pivotal attachment of a distorted-Z-shaped bar 10, as shown. The other end of said bar 10 has an ear 11 thereon to which is pivotally mounted at 11^a a 65 second bar 12, of the shape shown. The ear 11 is constructed with a shoulder 10^a, and the member 12 also has a shoulder 12^a, the same being so arranged that, when the chair is in the extended position illustrated in 70 Fig. 2, the said two shoulders contact with each other so as to maintain in a horizontal position those portions of the members 10 and 12 which are immediately adjacent the pivot 11^a. On each side of the table two 75 such members 10 and 11 are attached, and the pivot 11^a, which consists of a bar, joins each pair of said members, as shown. Referring again to the extended chair in Fig. 2, the vertical portion of the member 10^b 80 constitutes a supporting leg for the chair, as does also the lower portion 12^b of the member 12.

In the upper end of the member 12 is a pivot 15, to which is attached a seat panel 85 13 having a shoulder 16 adjacent the pivot, said shoulder retaining said panel 13 in horizontal position when the chair is extended. The lower side of said panel 13 is provided with a knob or handle 14, by means 90 of which the chair may be withdrawn from under the table.

Spring clips 17 are attached to the under-side of the panel 1 under which the shoulder 16 of the panel 13 slides, in concealing the 95 chair, thus retaining said chair from falling into extended position.

The manner of manipulating the device is now readily apparent. Assuming the chair is in extended position, the panel 13 is rotated through about 135 degrees, and the same is lifted upward and the member 10 is swung inward toward the table until the chair is entirely under the panel 1. Then the shoulder 16 lies under the clip 17 and is 100 retained thereby. In order to extend the chair, the knob 14 is simply withdrawn and the chair placed in the position shown in Fig. 2, the manner of extending the same being apparent.

In Figs. 3 and 4 I have illustrated my invention applied to a sewing machine 20 having a top panel 21 supported upon legs 22. Extensions or braces 23 are mounted upon the lower extremities of the legs 22, and at 24 in said braces are pivotally attached the members 10. Further description of the latter application is believed superfluous, since the parts are numbered similarly to those 10 described in the other figures of the drawings. The advantages of this application are great, for the constant location of the chair on hand for the machine will eliminate the troublesome search for, and carrying of, a chair from a distance. Again, the chair will not take up any additional space when not in use.

In Figs. 7 to 9, inclusive, I have illustrated modified forms of my invention applied to sewing machines. In Fig. 7, referring to the chair, the member 12^a has been turned at the top to provide a horizontal shoulder 25 having a raised pivotal support 26 at its extremity. The chair seat 13^a is pivoted at 26, and rests upon the said shoulder 25.

Since, in factories utilizing a large number of sewing machines, the machines are generally fixed to the floor, I have illustrated 30 in Fig. 8 the manner in which my chair may be well fixed to the floor adjacent the machine. The floor is shown at 32, and a base 30 having outer extensions 31 is screwed to the floor. Ears 33 stand upright from said base, and a pin or shaft 9^c passes through 35 said ears and pivotally retains therebetween the foot 34 of the leg 10^c, the latter being equivalent to the leg 10^a of Fig. 7.

Still another modification is illustrated in 40 Figs. 9 and 10, in which the chair is shown composed of a leg 10^e (equivalent to the afore-mentioned leg 10^a), said leg being attached at 24^e to the support 23^e on the machine 20. Another leg 12^e is pivotally attached to the leg 10^e at 11^e, a pair of right-

angled shoulders 27^e being provided on said legs so that the chair retains rigidity when extended. The member 12^e extends upward as at 47, being provided at the upper end with a pivotal mounting 26^e, to which the 50 seat panel 13^e is pivoted. A third leg 42-43 is pivotally attached at 42^e to the leg 10^e. A spring 41 is pivotally attached to the top of said leg 42 at 44, and when in use the seat 13^e rests upon the free end of said 55 spring. The member 47 is curved inwardly and downwardly at the top, in the form of a brace 40, and an additional brace 45 is attached both to said member 40 and the member 12^e. An additional link 41^e joins the top 60 of the member 45 and the spring 41. Thus, the seat is cushioned by said spring. The chair may be folded when not in use into the position shown dotted.

Fig. 10 illustrates, in enlarged detail, the 65 pivotal attachment of the seat 13^e to the member 47. This shows that the seat 13^e is supported on one side by the pivot 26^e and on the other by the spring 41, so that the aforementioned cushioning effect is attained. 70 As may be desirable, the seat 13^e is here illustrated as composed of a pair of horizontal slabs joined by a screw 46. The dotted lines of Fig. 10 show the position of the seat 13^e when folded back. 75

I claim:

A device of the class described comprising a frame, standards supporting said frame, collapsible chairs pivotally attached to said standards and adapted to be concealed under 80 said frame, said chairs comprising substantially Z-shaped members having pivotal attachment with said standards, leg members pivotally attached to said Z-shaped members, upward extensions on said leg members, seat panels pivotally attached to said extensions, and means on said seat panels for retaining the latter in horizontal position when said seat is extended. 85

FRANK MARZAK.
